UNITED STATES PATENT OFFICE.

HENRY O. DAVIS, OF PLYMOUTH, MASSACHUSETTS.

NAILING PLATE FOR LASTS.

Application filed September 16, 1926. Serial No. 135,767.

This invention relates to a nailing plate of hard metal, attachable to the bottom of a wooden last, and adapted to clinch the points of nails or tacks driven into parts of a shoe on the last. The plate is provided with an orifice adapted to receive a nail driven through an inner sole and into the wooden body of the last, to temporarily secure the inner sole prior to the lasting operation. The orifice is necessarily of much larger diameter than the nail, to prevent difficulty in locating the nail, so that it will pass through the orifice when the latter is concealed by the inner sole. The usual diameter of the orifice is such that a portion of the inner sole is liable to be bulged into the opening by the pressure exerted on the sole during the sole-leveling and other operations, so that in the completed shoe, the inner sole is liable to have a protuberance projecting into the foot-receiving space.

My invention has for its object to provide a nailing plate, adapted to prevent the formation of the above-mentioned protuberance, and to be supplied at a reasonable cost to last makers, ready for attachment to a last.

The invention is embodied in a nailing-plate having a puncture-resisting clinching portion surrounding a large nail-receiving orifice, and a penetrable nail-engaging portion filling the orifice and interlocked with the margin thereof, the sides of the two portions being preferably substantially flush with each other, so that the plate is attachable, as usual, to a last bottom, and presents a continuous lower side, preventing the bulging of the nail-receiving portion of an inner sole bearing thereon.

Of the accompanying drawings forming a part of this specification,—

Figure 1 is a side view, showing a nailing plate having a nail-receiving orifice as usually formed.

Figure 2 is a side view, showing the orifice prepared in accordance with the invention, to engage the nail-engaging portion hereinafter described, the top side of the plate being shown.

Figure 3 is a view similar to Figure 2, showing the bottom side of the plate.

Figure 4 is a view similar to Figure 2, showing the nail-engaging portion engaged with the margin of the orifice.

Figure 5 is a side view of the nail-engaging portion.

Figure 6 is a section on line 6—6 of Figure 4.

Figure 7 is an enlargement of a part of Figure 2, the clinching portion being shown in perspective.

Figure 8 is an enlargement of a part of Figure 4, the clinching and nail-engaging portions being shown in perspective.

Figure 9 is a view similar to Figure 6, showing the completed plate attached to a last, and a nail driven through an inner sole, and the nail-engaging portion into a last.

Figure 10 is a fragmentary sectional view, showing a modification.

Figure 11 is a fragmentary sectional view, showing another modification.

The same reference characters indicate the same parts in all of the figures.

The nailing-plate 12, shown by Figure 1, is formed to cover the heel portion of the bottom of a wooden last, and is provided with the usual large orifice 13, for the reception of the nail 15 (Figure 9), which temporarily secures the inner sole 16 to the last 17, the plate being attachable to the last by nails driven through nail holes 19 in the plate, one of said nails, designated by 18, being shown by Figure 9.

In carrying out my invention, I provide a nailing-plate comprising a clinching portion, formed by the plate 12, and a penetrable nail-engaging portion 20, surrounded by and interlocked with the clinching portion, the sides of said portions being substantially flush with each other, as shown by Figure 6, so that the plate is adapted to be attached, as usual, to the last, and has a bottom surface adapted to support the portion of the inner sole 16, through which the nail 15 is driven, without permitting said portion to bulge into the large nail-receiving opening.

The clinching portion 12 may be of any suitable hard metal, such as iron or steel, while the nail-engaging portion 20 may be made of any suitably strong and durable sheet material, which is adapted to be punctured by the nail 15, and is sufficiently compressible and conformable to permit its margin to be conformed by pressure to the margin of the orifice in the clinching portion, so that a lock joint is formed, the margin of said orifice being diversified and formed to constitute a lock joint element. The nail-engaging portion 20 is preferably a disk, cut

from a sheet of indurated fiber made of compressed pulp.

In preparing the usual plate 12, to constitute the clinching portion of my improved plate, I diversify the margin of the orifice 13, so that said margin is adapted to constitute an element of a lock joint. This is preferably accomplished by indenting one side of the plate or clinching portion 12, as best shown by Figures 2 and 7, to form segmental seat portions 22, segmental edge portions 23, at the outer edges of the seat portions, and radial edge portions 24, at opposite ends of the seat portions. These portions may be formed by a suitable die, adapted to displace portions of the metal toward the under side of the plate, some of the displaced metal being indicated by dotted lines in Figure 7, this being subsequently ground off to flatten the under side of the plate. The diameter of the disk forming the nail-engaging portion 20, is such that when the disk is placed on the upper side of the clinching portion 12, and subjected to pressure, the marginal portion of the disk is conformed to the diversified margin of the orifice and firmly interlocked therewith, so that the nail-engaging portion 20 is practically inseparable from the clinching portion 12. The orifice margin may be diversified as above described, by a single operation, and the nail-engaging portion may be engaged with the diversified margin by another single operation, so that the cost of production is reduced to a minimum.

I have found that the nail-engaging portion 20, made of indurated fiber, is sufficiently strong and durable, and may be penetrated many times by a nail 15, without becoming inoperative, the durability of said portion being practically as great as that of a wooden last.

The margin of the orifice in the clinching portion 12, may be otherwise diversified, as shown, for example, by Figure 10, which shows a margin provided with beveled faces 26, to which the margin of the nail-engaging portion 20 is conformed, to form a lock joint.

It is obvious that the invention is not limited to a heel plate, and may be embodied in a plate formed for application to the toe portion of a last bottom, or to a full length nailing plate formed to cover the entire bottom of the last, and provided with a plurality of nail-engaging portions 20.

As shown by Figure 11, the nail engaging portion, here designated by 20^a may be positively connected with the plate by forcing said portion under pressure into an orifice 13, the wall of which is not diversified, the portion 20^a being somewhat thicker than the plate 12, and forming a slight protuberance on the inner side of the plate, the last being provided with a shallow cavity 27 in its

bottom to receive said protuberance. It is not essential, therefore, that the upper side of the nail-engaging portion be exactly flush with the upper side of the plate.

It will be seen that in each of the illustrated embodiments of the invention, the portions 12 and 20, or 20^a are positively united, prior to the attachment of the device to a last, so that said portions collectively constitute an article of manufacture, adapted to be stored and handled as a unit, and attached as a unit to a last. In each of the forms shown by Figures 1 to 10, inclusive, said unit is attachable without any adaptation of the last other than the formation therein of the usual recess to receive the entire plate 12, and locate the bottom of the plate flush with the bottom of the last. In the form shown by Figure 11, the only modification of the last is the formation of the shallow cavity 27.

I claim:

1. As an article of manufacture, a nailing-plate having a puncture-resisting clinching portion and a puncturable nail-engaging portion surrounded by and interlocked with the clinching portion, said portions being positively connected, so that the plate is attachable as a unit to a last.

2. As an article of manufacture, a nailing-plate having a metallic puncture-resisting clinching portion, and a non-metallic compressible and puncturable nail-engaging portion, surrounded by and interlocked with the clinching portion, said portions being positively connected, so that the plate is attachable as a unit to a last.

3. As an article of manufacture, a nailing-plate comprising a metallic puncture-resisting body portion having a nail-receiving orifice within its margin, of much greater diameter than the nail intended to be received, and a puncturable nail-engaging portion filling said orifice and interlocked with the margin thereof, said portions being positively connected, so that the plate is attachable as a unit to a last.

4. As an article of manufacture, a nailing-plate comprising a metallic puncture-resisting body portion having a nail-receiving orifice within its margin, of much greater diameter than the nail intended to be received, the margin of said orifice being formed to constitute an element of a lock joint, and a nail-engaging portion of compressible and puncturable material filling said orifice and marginally conformed to the margin of the orifice, to form a lock joint, said portions being positively connected, so that the plate is attachable as a unit to a last.

5. As an article of manufacture, a nailing-plate comprising a metallic puncture-resisting body portion having a nail-receiving orifice within its margin, of much great-

- er diameter than the nail intended to be received, the margin of said orifice being formed to constitute an element of a lock joint, and a nail-engaging portion of indurated fiber filling said orifice and marginally conformed to the margin of the orifice to form a lock joint, said portions being positively connected, so that the plate is attachable as a unit to a last.
- 10 6. As an article of manufacture, a nail-plate comprising a metallic puncture-resisting body portion having a nail-receiving orifice within its margin, of much greater diameter than the nail intended to be received, the margin of said orifice being di-

versified to constitute an element of a lock joint, and including segmental seat portions, segmental edge portions at the outer edges of the seat portions, and radial edge portions at opposite ends of the seat portions, and a nail-engaging portion of compressible and puncturable material filling said orifice and marginally conformed to the said diversified margin, to form a lock joint, said portions being positively connected, so that the 25 plate is attachable as a unit to a last.

In testimony whereof I have affixed my signature.

HENRY O. DAVIS.
